UNITED STATES PATENT OFFICE.

MILLARD B. HODGSON, OF ROCHESTER, NEW YORK, ASSIGNOR TO EASTMAN KODAK COMPANY, OF ROCHESTER, NEW YORK, A CORPORATION OF NEW YORK.

DENTAL X-RAY PACKAGE.

Application filed October 7, 1926. Serial No. 140,133.

This invention relates to dental X-ray film packets and particularly to such packets having a tab adapted to be gripped between the teeth of the patient to position the packet during exposure. This invention is an improved embodiment of the invention disclosed in the patent to Raper, 1,467,876 granted September 11, 1923.

Such packets heretofore have either had the tab near the middle, to be used in taking inter-proximal exposures, or near one edge, to be used in taking root exposures. One object of my invention is to furnish a package in which a single tab may be used for either purpose. Another object is to utilize the tab as a means for opening the package. Other objects will appear from the following description, reference being made to the accompanying drawing, wherein the same reference characters denote the same parts throughout; and in which

Fig. 1 is a perspective view of a package embodying my invention;

Fig. 2 is a side view of a package showing certain parts in section;

Fig. 3 is a perspective view of my preferred form of tab;

Fig. 4 is a top view of another embodiment of my invention;

Fig. 5 is a section on an enlarged scale taken on line 5—5 of Fig. 4;

Fig. 6 is a top view of still another embodiment;

Fig. 7 is a perspective view of a different embodiment;

Fig. 8 is an edge view of another embodiment.

The package in which my invention is shown as incorporated in Fig. 1 is of the type disclosed in Patent No. 1,441,160, Lovejoy granted January 2, 1923, and the wrapping of which consists of a sheet of material 1, preferably paper, covering one side of the package and bent around the edges at 2, and held in place by an adhesive coated sheet or label 3. Beneath one edge of the label 3 is inserted the end 4 of a tab 5 which is bent around the edge of the package and across the opposite surface 1 against which it lies flat, as manufactured and sold. The tab is preferably scored or weakened along transverse lines 6 and 7, one of which is near the edge of the package while the other is along the median line of the package. Suitable directions may be printed on the tab, as at 8.

The tab may consist, as shown in Fig. 2, of a single piece of rather stiff paper or of cardboard 9', or it may consist, as shown in Fig. 3, of a sheet of metal foil 9 preferably aluminum, upon each surface of which is cemented a sheet of paper 10, making a laminated tab, having the advantages, inherent in a metal foil, of being readily impressionable and the advantages of paper of being easily written or printed on.

The tab may have a small amount of adhesive on the under side as at 20, so that when used for interproximal exposures it will be made to adhere to the package. This may be waterproof adhesive by which the tab adheres lightly to the package but which permits it to be stripped therefrom at the end, when used as shown in dotted lines in Fig. 1, or it may be a soluble adhesive that is moistened only when used. Only a light degree of adhesive is necessary in any event.

The tab may be bent up along the line 6, as indicated in dotted lines in Fig. 1, when an exposure is to be made of certain entire teeth, including the roots of one jaw. The user then bites or grips the tab between his teeth and holds the tab in such position that it will lie almost entirely behind one jaw and will extend behind the roots. If the tab is bent along line 7, it will extend up from the center of the package, as shown in Fig. 2, and when gripped between the teeth will lie behind the crowns of the teeth of both jaws.

After exposure, the operator may open the packet in the dark room by means of the tab which may be pulled so as to rip open or remove the label on sheet 3, thus opening up the package.

Figs. 4 and 5 illustrate my invention as embodied in a packet of the type that includes a sheet of metal foil 11, bent around the edges of the package to form an overlying flange 12, and held in place by a sheet 13. Overlying this sheet 13 is a tab 14. The sheet 13 overlies the flange 12 except for the part covered by tab 14. At each edge 15 of tab 14, the flange 12 has small slits, and at these points the sheet 13 passes beneath the tab and the flange, the latter being bent down over the tab. An additional sealing strip of paper 16 may be placed across this end of the packet, the edge 17 of which constitutes an abutment against which the tab may be bent up for the purpose of taking

root exposures. In Fig. 5 are shown the usual sheets of sensitized film 18 and protective paper 19. The tab 14 is continued around the edge of the package, as shown 5 at 15', under sheet 11, and may be used to rip off this sheet 11, thus opening the package.

The packet shown in Fig. 6 is similar to that just described except that the sealing 10 strip 16 is omitted.

In Fig. 7 is shown a package of the type including a sheet of paper 19' across one surface, upon which is bent as a flange 21, the edge of a sealing sheet of material 22 15 covering the other surface and bent around the edge. This may be of metal foil or of paper, and is held in place either by adhesive or by the crimping of the material. From one edge, an integral tab 23 is 20 continued which constitutes an opening tab and also is to be gripped by the teeth of the user as already described.

The form shown in Fig. 8 is similar to that shown in Fig. 2 except that the tab 24 25 is integral with the sealing sheet or label 25.

In all of the forms described it is to be noted that the tab is so joined to a part of the wrapper that it can be used to open the package, and that the tab is in each case attached to the package adjacent one edge, and is adapted to be bent at two different points as desired for use during the exposure. The material of the tab is impressionable in that it may be bent at the desired 35 points of flexure without cracking and will retain the shape into which it is bent.

It is obvious that numerous other embodiments are possible and I contemplate as within my invention all such modifications and equivalents as fall within the scope of the appended claims.

Having thus described by invention, what I claim as new and desire to secure by Letters Patent is,

1. A dental X-ray film package having an impressionable tab attached thereto adjacent one edge and having a free portion exterior of the package lying flat upon the package and extending over half way across the package, and being bendable on a line near the edge of the package and also on a line bisecting the package transversely of the tab.

2. A dental X-ray film package having attached thereto adjacent one edge a tab the

length of which is greater than one half the 55 distance from said edge to the opposite edge, said tab being scored transversely near its base and also on a line midway of the package whereby the tab may be readily bent at either place.

3. A dental X-ray film package having a sealing sheet, a flexible tab joined to said sealing sheet adjacent one edge of the package and constituting a tab whereby the package may be opened, said tab extending over 60 65 halfway across one face of the package from said edge.

4. A dental X-ray film package having a sealing sheet, an impressionable tab joined to said sealing sheet adjacent one edge of 70 the package and constituting a tab by which the package may be opened, said tab having a free portion exterior of the package extending over half way across said package 75 from said edge and being readily bendable on a line near the edge of the package and also on a line bisecting the package transversely of the tab.

5. A dental X-ray film package having a sealing sheet, an impressionable tab joined 80 to said sealing sheet adjacent one edge of the package and constituting a tab by which the package may be opened, said tab extending over half way across said package from said edge and having weakened transverse lines 85 near its base and at an intermediate point in its length, whereby it may be readily bent near the edge of the package and on a line midway of the package.

6. A dental X-ray film package having on 90 one surface a sealing sheet, a tab extending from said sheet near the edge of the package and attached to the package by the sheet and constituting a means by which the sheet may be torn from the package and the package 95 thereby opened, the tab having a length greater than one half the distance across the package and comprising a sheet of impressionable metal foil and a strip of paper laminated together, and having transverse 100 scored lines adjacent its base, whereby it may be readily bent near the edge of the package, and also at an intermediate point, whereby it may be readily bent on a line 105 midway of the package.

Signed at Rochester, New York this 4th day of October, 1926.

MILLARD B. HODGSON.
